HYDRAULICALLY OPERATED SURFACE
GRINDING MACHINEWallace H. Wood, Worcester, Mass., assignor to
Norton Company, Worcester, Mass., a corpora-
tion of Massachusetts

Application July 1, 1935, Serial No. 29,225

10 Claims. (Cl. 51—233)

This invention relates to grinding machines, and more particularly to a hydraulically operated surface grinding machine.

In the grinding of plane surfaces, it has been standard practice to use the peripheral face of a grinding wheel and to provide a reciprocating work table opposite the peripheral face of the grinding wheel to support the work piece to be ground. Either the table or the wheel is mounted so that the work and wheel may be fed relatively toward or from each other to grind the work piece to the desired thickness. Such machines have also included a transverse feeding mechanism, so that the grinding wheel and the work may be fed transversely relative to each other so that a work piece surface of greater width than the operative face of the grinding wheel may be accurately ground to a plane surface. These machines have required the constant attention of the operator to control the transverse and vertical feeding movement so that the wheel and work may traverse transversely relative to each other to grind across the face of a wide piece of work. The prior patent to Whittles No. 1,978,181 improved the standard practice in surface grinding machines, in that it provided an automatic and self-reversing transverse feeding mechanism which served to automatically traverse the wheel and work transversely relative to each other so that the wheel is indexed intermittently at the end of the table stroke by successive increments until the wheel has ground the entire work face and then automatically reversed so that the wheel and work are fed by intermittent increments in the reverse direction. This automatically reversible transverse feed continues until the operator stops the transverse feed.

It is one of the objects of this invention to provide a hydraulically controlled surface grinding machine with an automatic cross feed transverse feeding mechanism which automatically feeds the wheel and work table transversely by intermittent increments until the wheel has ground across the entire surface of the work and then automatically allows the work supporting table to move to an inoperative or loading position beyond the normal reciprocatory stroke thereof and automatically stops the table in this predetermined loading position.

It is another object of this invention to provide a grinding machine in which the work table is moved longitudinally and transversely by hydraulically actuated mechanisms.

It is still another object of this invention to provide a surface grinding machine with a hydraulic

table reciprocating mechanism which is interconnected with a hydraulically actuated wheel feeding mechanism and serves to feed the work table transversely relative to the grinding wheel at the ends of the work table stroke. 5

It is a further object of this invention to provide a transverse control mechanism which automatically moves the work table transversely by intermittent increments at either or both ends of the table stroke. 10

It is still a further object of this invention to provide a transverse work table control mechanism which serves after the table has moved a predetermined distance by intermittent movement at the end of the table stroke to render the table reversing mechanism inoperative and allow the table to move beyond its normal stroke to an inoperative loading position and then stop in a loading position. 15

It is another object of this invention to provide a fluid pressure table reciprocating mechanism which is provided with a double end piston rod having readily detachable connections between the opposite ends of said piston rod and the adjacent ends of the work table. 20

Other objects will be apparent from the foregoing description. 25

One form of this invention has been illustrated in the accompanying drawings in which like reference numerals indicate like parts: 30

Fig. 1 is a perspective view of the improved grinding machine, having parts broken away and shown in section to more clearly show the operating mechanism; 35

Fig. 2 is a fragmentary plan view, on an enlarged scale, of the hydraulic piston and cylinder and the cross feed mechanism; 35

Fig. 3 is a fragmentary front elevation of the cross feed mechanism, having parts broken away and shown in section; 40

Fig. 4 is a fragmentary cross-sectional view through the table operating mechanism, showing the cylinder and the control valve in section and the manual traverse mechanism; 45

Fig. 5 is a vertical section through the control valve, taken approximately on the line 5—5 of Fig. 4; 50

Fig. 6 is a fragmentary end elevation of Fig. 3, having parts broken away and shown in section to clarify the illustration; 50

Fig. 7 is a fragmentary view, partly in section, on an enlarged scale, of the reverse lever and the transverse feed control valve; 55

Fig. 8 is a fragmentary sectional view, taken approximately on the line 8—8 of Fig. 7; 55

Fig. 9 is a fragmentary view of the reverse lever and transverse feed control valve similar to that shown in Fig. 7, but with the parts in a different position;

- 5 Fig. 10 is a piping diagram of the fluid pressure operating mechanism; and

Fig. 11 is a horizontal sectional view, taken approximately on the line 11—11 of Fig. 3.

As illustrated in the drawings, the machine 10 embodying this invention comprises a base 10 which supports a vertically movable wheel slide 11 adapted to slide in the vertical slideways 12 and 13. The wheel slide 11 carries a horizontally positioned wheel spindle 14 journalled in suitable bearings 15 and 16 on the slide 11. The wheel slide 11 is adapted to be raised or lowered to feed the grinding wheel relatively toward and from the work surface by means of a feeding mechanism comprising a screw 18 which meshes 20 with a nut 19 formed as an integral part of the base 10 or fixedly mounted thereto. The feed screw 18 is rotatably supported in bearing 20 and carries at its upper end a bevel gear 21 meshing with a bevel gear 22 on a horizontal shaft 23 which is also journalled in a projection of the wheel slide 11. The shaft 23 carries a manually operable feed wheel 24 which may be rotated in either direction, depending upon whether it is desired to raise or lower the position of the 30 grinding wheel.

Transversely movable carriage

A transversely movable carriage 28 is arranged to slide transversely relative to the base 10. The carriage is provided with a pair of spaced flat ways 29 and 30 which mate with corresponding flat ways on the base 10. A suitable transverse guide gibbed slideway 31 is provided which is parallel to the ways 29 and 30 and midway therebetween to serve as a guiding means to guide the carriage 28 transversely relative to the base 10.

Longitudinally movable table

A longitudinally movable work supporting table 33 is supported on the usual V-way 34 and flat way 35 for a longitudinal reciprocating movement relative to the carriage 28. A work piece 36 may be held on the upper surface of the table 33 while its upper plane surface is ground to the desired extent.

In this type of machine, as illustrated, the grinding wheel is arranged to move in a vertical direction toward and from the work, and the work supporting table is arranged to be moved longitudinally and traversed transversely in order that the entire plane surface of a work piece may be ground to the required extent.

Hydraulic system

- 60 A fluid pressure mechanism is provided to reciprocate the longitudinally movable work table. In the form illustrated, a cylinder 40 is fixedly mounted on the upper surface of the transversely movable carriage 28 by means of brackets 41 and 42. The cylinder contains a piston 43 which is fixedly mounted to a piston rod 44 which extends through cylinder heads 45 and 46. Each end of the piston rod 44 is connected to brackets 47 and 48 depending from the longitudinally movable table 33. In the preferred construction, the piston rod 44 is detachably connected to the table brackets 47 and 48 so that the fluid pressure system may be readily disconnected from the table, if desired, when it is desired to traverse or reciprocate the machine manually. In the pre-

ferred construction, the brackets 47 and 48 are provided with an aperture sufficiently large to allow nuts 50 and 51 to slide through the aperture when the rod 44 is disconnected. Each bracket 47 and 48 is provided with a dovetailed 5 slideway 52 (Figs. 1 and 2) and having a vertically movable slide 53 and 54 which is arranged to straddle the piston rod 44 and connect the piston rod 44 to the table 33 when the slide is in a downward position. When it is desired to disconnect 10 the fluid pressure piston and cylinder from the table to permit manual operation thereof, slides 53 and 54 are raised so as to allow the table to slide longitudinally without carrying the piston rod 44 therewith.

15 The base 10 is formed as a hollow box-like construction in which the lower portion serves as a reservoir 53 for the fluid pressure system. Fluid is drawn from the reservoir 53 through a pipe 54 by a pump 55 and is forced through a 20 pipe 56 to a table control valve 57. A relief valve 58 is provided in the pipe line 56 and is arranged to allow fluid under pressure to by-pass through a pipe 59 and return to the reservoir 53 in case the pressure within the fluid pressure system increases above a desired and predetermined pressure.

25 The control valve in this application is identical with the control valve shown and described in the copending application Serial No. 741,119 30 filed August 23, 1934. The control valve 57 combines the functions of a reversing valve and a pilot valve. A reversing lever actuated by the table movement serves to move the valve to a center position and then the fluid under pressure serves to move the reverse or control valve in a reverse direction, producing a smooth reversal of the table movement without the necessity of providing a complicated series of actuating mechanisms and pipe connections. In the 40 form illustrated, a piston type valve (Figs. 1 and 5) is provided including a movable valve member 65 having a plurality of pistons 66, 67, 68, 69 and 70 integrally formed thereon. Fluid under pressure is forced through a pipe 56 into a pipe 45 (Fig. 10) and chamber 71 (Fig. 5) within the valve casing 57. Assuming the valve is not in a central or neutral position (Fig. 10), fluid under pressure is conveyed from the chamber 71 through either ports 72 or 73 into valve chamber 50 74 or 75 respectively. The valve chambers 74 and 75 are formed between the valve pistons 67 and 68, 69 and 70 respectively.

55 When the valve stem 65 is moved in either direction from the neutral position illustrated in Fig. 5, fluid under pressure passes either from the valve chambers 74 or 75 through port 76 or 77 respectively, then through pipe 78 or 79 respectively, through cylinder head 45 or 46, into cylinder chamber 80 or 81 to move piston 43 and 60 traverse the table longitudinally.

When valve stem 65 is moved in either direction from the position illustrated in Fig. 5, fluid under pressure may pass from valve chamber 74 or 75 through port 72 or 73, through port 87 or 65 88 respectively, into valve chamber 89 or 90. The valve chambers 89 and 90 are formed between valve pistons 66 and 67, 69 and 70 respectively. Fluid under pressure passes from chambers 89 or 90, through port 94 or 95, into a small 70 reservoir 96 or 97. The overflow from reservoirs 96 and 97 is returned to the main reservoir or sump 53 in the base 10.

The effective areas of valve pistons 66 and 70 is considerably less than the effective areas of

valve pistons 67 and 69 respectively. By providing the differential in pressure areas between these valve pistons, the valve chambers 89 and 90 serve to function as a pilot valve and cause a reversal of the reversing valve under the influence of fluid pressure whenever the valve is moved to a position slightly by the center position, as shown in Fig. 5; that is, so that either the port 87 or the port 88 is cut off to a greater extent than the other, allowing fluid under pressure to flow into either chamber 89 or 90. Due to the differential piston areas, the fluid under pressure entering chambers 89 or 90 serves to move the valve piston 65 either towards the right or towards the left, as viewed in Fig. 5.

Speed control valve

A speed control or throttle valve 100, as illustrated in Figs. 1 and 5, is formed integrally with the valve 57. As illustrated diagrammatically in Figs. 1 and 10, the valve 100 is shown as a separate valve unit. The valve 100 is preferably located in the exhaust side of the system so as to maintain a uniform pressure on the operative side of the table operating piston 43. This valve comprises a valve stem 101 which is provided with valve pistons 102 and 103. The valve piston 103 is provided with a V-shaped notch 104 which is located at one end of a pipe or passage 105. The fluid passes from either of the valve chambers 74 and 75 through the V-port 104, throttle valve 100, and exhausts through a passage or outlet pipe 106 into the reservoir 53 in the base 10.

The throttle valve is arranged so that it may be moved longitudinally from a full line position (Figs. 1 and 4) to a dotted line position. The valve is provided with an actuating knob 110 on the front end of the valve stem 101, which permits the valve to be rotated. In the preferred construction, the valve piston 103 is provided with a V-shaped notch which serves as a V-port to throttle fluid passing therethrough. It is possible to obtain a fine adjustment by cutting off more or less of the V-port to precisely regulate the exhaust of fluid from the system and thereby permit a fine regulation of the table speed.

In order that the valve piston 103 may be maintained in the desired adjusted position so as to enable the table to be stopped and started as desired without changing the speed adjustment, a serrated or notched portion 113 is provided and a spring pressed pawl 114 is carried by the valve casing 100, so that when the knob 110 is turned to adjust the valve piston 103 to give the desired table speed, the pawl 114 engaging notches in the portion 113 serves to hold the piston in its adjusted position, so as to permit moving the valve stem 101 by means of a control lever 115 to start and stop the table movement without upsetting the adjustment of the valve. The control lever 115 is fixedly mounted on the upper end of a rock shaft 116. The lower end of the rock shaft is provided with a yoked member 117 which engages a groove 118 in knob 110. An adjustable dog 119 on the table serves to engage a projection 120 on lever 115 and automatically shift the throttle valve to a closed position to stop the table movement when it has been moved to an inoperative or loading position.

In the preferred construction, a yieldable connection, such as a spring 112, is provided between the yoked member 117 and rod 116. The parts are so arranged that when dog 119 en-

gages lever 115, the valve 100 will be positively moved to a closed position. The spring 112 serves to allow the knob 110 to be moved inwardly to open the throttle valve and start the table when the lever 115 is in engagement with the dog 119.

Fluid by-pass

When the throttle valve 100 is in a closed position, stopping the table movement, it is desirable to provide a suitable fluid by-pass whereby fluid may readily pass from one end of the cylinder to the other to facilitate manual movement of the table. In the preferred construction, a passage or pipe 122 is provided to connect the pipe 79 and valve chamber 75 with a passage or pipe 123 provided as an extension of the pipe 78, so that when the throttle valve 100 is in a closed position, as indicated in broken lines in Fig. 10, fluid may readily pass from cylinder chamber 80, through pipe 78, pipe 123, through a valve chamber 124, between the valve pistons 102 and 103, and out through pipe 122, pipe 79, into cylinder chamber 81. This by-pass in the throttle valve interconnects the cylinder chambers 80 and 81 so that when the fluid pressure system is shut off by closing the throttle and control valve 100, the table 33 may then be moved manually, if desired, without being retarded by fluid pressure within the system.

In order to relieve the pressure from reversing valve 57 when the throttle valve is in a closed position, a second by-pass is provided including a chamber or pipe 121 which connects with fluid pressure pipe 56 so as to allow fluid to by-pass from pipe 56 through pipe 121, valve chamber 125, and to exhaust through a passage or exhaust pipe 106 into the reservoir 53. By providing this latter by-pass, fluid pressure is relieved from the reversing valve so as to enable the operator to readily shift the reversing valve without moving the valve against the fluid pressure from the pump.

Manual traverse

In order that the table 33 may be moved or traversed manually, a suitable hand wheel 126 is mounted on the outer end of a shaft 129 on the front of the machine base. This wheel rotates a gear 127 mounted on the inner end of shaft 129 which meshes with a rack 128 depending from the longitudinally movable table 33. The shaft 129 is arranged so that it may be moved axially so that when the table 33 is reciprocated by means of the fluid pressure piston and cylinder, the shaft is moved outwardly toward the operator with the hand wheel 126 in the full line position as indicated in Fig. 4. In this position, the gear 127 is out of mesh with rack 128 so that the hand wheel 126 remains stationary during the power reciprocation of the work table 33. When it is desired to traverse the table 33 manually, the operator moves the hand wheel 126 (Fig. 4) into the broken line position 126a which serves to move the gear 127 into position 127a (Fig. 6) in mesh with the rack 128, so that when the wheel 126 is rotated, a traversing movement of the table will be obtained.

Transverse work feed

The transversely movable carriage 28 is arranged for a transverse movement relative to the base 10 and the grinding wheel. This may be accomplished by means of a rotatable screw 130 which is supported in bearings 131 and 132 on the carriage 28. The screw 130 meshes with a nut 75

133 which is fixedly mounted on the base 10. It will be readily apparent from this disclosure that upon rotation of a hand wheel 134 on the outer end of the screw 130, the carriage 28 may be moved transversely to change the position of the work piece relative to the grinding wheel. The transverse feeding movement of the work support is essential in a machine of the surface grinder type inasmuch as it is frequently necessary to 10 grind a plane surface which is of greater width than the width of the grinding wheel. The work table and wheel are reciprocated longitudinally relative to each other and a relative transverse movement is provided so that on successive relative reciprocations between the work and wheel, a relative transverse movement may be obtained so that the wheel operates on a different portion of the work, so that the entire surface of the work may be accurately ground to a plane surface.

20   *Automatic reversal—work table*

A suitable reversing mechanism is provided to change the direction of movement of the table 33 as desired. In the preferred construction, adjustable dogs 140 and 141 are adjustably mounted in a T-slot 142 on the table 33. The dogs 140 and 141 are arranged to engage the inner end of a reverse control lever 143 which is pivotally mounted on a vertically rotatable sleeve 30 144 which is journaled in the transverse movable carriage 28.

In order that the table may be reversed with a minimum amount of vibration, it is desirable to provide a lost motion connection between the reversing lever and the reversing valve, so that during the initial movement of the reversing lever under the influence of the table dogs, the valve is not moved. This mechanism preferably comprises a relatively short lever 145 mounted on the 40 lower end of sleeve 144. A pivotally mounted plate or lever 146 is supported on a stud 147 on carriage 28. The lever 146 is provided with a pin 148 engaging a groove 149 on the reverse valve stem 65. A suitable yieldable connection is provided between the levers 145 and 146 which comprises a link 150 pivotally connected by a stud 151 with lever 146. The link 150 slidably supports a second link 152 which is pivotally connected to lever 145 by means of a stud 153. A spring 154 is interposed between projections of the links 150 and 152 so that when the reverse lever 143 is moved in either direction by means of the dogs 140 and 141, the spring serves to take up the initial movement so that the movement of the reversing valve may be picked up without a sudden shock or vibration being transmitted thereto. It will be readily apparent from the foregoing disclosure that when the throttle valve is moved to start the table movement, the 50 table 33 will reciprocate under the influence of fluid under pressure within the cylinder 40, and the length of the reciprocatory stroke will be governed by the position of adjustable dogs 140 and 141. The dogs engaging the reversing lever 65 143 serve to shift the reversing valve member 65 so as to automatically change the direction of movement of table 33, as desired.

Power operated wheel feeding mechanism

70   It is desirable to provide a suitable power actuated means for causing a transverse movement of the carriage 28 to cause a transverse movement of the work piece relative to the grinding wheel, so that the grinding wheel will grind a different 75 path across the face of the work at each recipro-

cation thereof. In the preferred construction, a fluid pressure actuated power feed is provided which is operated in timed relationship with the table reciprocating mechanism so that the transverse feeding movement of the carriage takes place during the period of reversal of the longitudinally movable work table.

As illustrated in the drawings, a forward and reverse feed are obtained by the gear mechanism, as illustrated in Figs. 2 and 3, comprising gears 158 and 159 mounted on the outer end of the feed screw 130. The gears 158 and 159 are mounted on a slidable sleeve 160 which is slidably keyed to the feed screw 130. The sleeve 160 may be moved axially by a reversing lever 161 having a yoked portion engaging a groove in the outer periphery of the sleeve 160. In the position of parts illustrated in Fig. 2, lever 161 is in the forward position, meshing the gear 159 with an idler gear 162 which also meshes with a driving gear 163 mounted on a shaft 164, to cause a transverse movement of the slide 28 towards the front of the machine. If it is desired to move the carriage away from the front of the machine or in the reverse direction, the operator shifts the 25 lever 161 from the full line position as indicated in Fig. 2 into the dotted line position 161a which serves to slide the sleeve 160 downwardly (Fig. 2) so that the gear 158 meshes directly with the driving gear 163. If it is desired to cause a 30 manual transverse feeding movement, the lever 161 is moved into a central or neutral position, as indicated by dotted position 161b, which serves to slide the sleeve 160, disengaging both gears 158 and 159 so as to allow free rotation of the 35 feed screw without turning the gear mechanism.

In order to rotate the driven gear 163, a fluid pressure cylinder 166 is provided on the carriage 28. This cylinder 166 contains a piston 167 which has a rack formed on its outer end. The rack 168 meshes with a pinion 169. The pinion 169 is connected to a pawl-carrying lever 170 having a pawl 171 engaging a ratchet wheel 172 which is fixedly connected with the driving gear 163. It will be readily apparent that when fluid is admitted to a 45 cylinder chamber 173, it serves to move the piston towards the left, as viewed in Fig. 2, against the tension of a spring 174, to move the rack 168, causing the pinion 169 to rotate in a counter-clockwise direction carrying the pawl 171 which 50 in turn rotates the ratchet wheel 172, gear 163, and serves to rotate the feed screw 130 in either direction, depending upon whether the gear 158 or gear 159 is in operative mesh.

In order to regulate the extent of movement 55 of the pawl and thereby regulate the extent of transverse movement of the carriage, an adjusting means is provided which in the present case comprises an adjustable stop screw 176 which is arranged in the path of the rack 168 to limit its motion, as caused by fluid under pressure, and thereby restrict and limit the movement of the feed pawl. The spring 174 serves to return the rack, piston and pawl to an inoperative position after the pressure has been relieved within the 60 cylinder chamber 173.

In order that the transverse carriage feed may be actuated in timed relation with the table reciprocation so that the transverse feed takes place at the end of the table stroke, it is desirable to 70 provide a suitable control valve which is actuated in timed relation with the table reversing mechanism so that the feeding mechanism may operate in the desired and timed relation with the table movement. As illustrated in the drawings, a con- 75

tral valve 180 is provided having a piston 181. The valve piston 181 is preferably arranged so that it may be actuated in timed relation with the reversing lever 143. In the preferred construction, a cam 182 which is moved by or in timed relation with the lever 143 serves to engage a roller 183 mounted on the end of the valve piston 181 so that the valve pistons may be moved when the reversing lever is shifted. In the position illustrated in Fig. 9, fluid is conveyed to the control valve through a pipe 184 into a valve chamber 185 and in the position of the valve, as illustrated in Fig. 9, out through a port 186 and a pipe 187 to the feed cylinder chamber 173. When the valve piston 181 moves into a position, such as that shown in Fig. 7, the fluid under pressure may exhaust from feed cylinder 173 through pipe or passage 187 through port 186, valve chamber 185, port 190 and pipe 191 to return to the reservoir within the base of the machine. A spring 192 within the valve piston 181 serves to hold the piston in a direction toward the left, tending to hold the piston up against a stop plate 193, which limits its movement towards the left.

In grinding various pieces of work, it is desirable to at times provide a transverse feeding movement of the work table relative to the wheel at each end of the table reciprocation or in other types of grinding, it may be desirable to feed at only one end of the table stroke, depending upon the surface being ground and the nature of the work and the finish desired.

A feed control mechanism is provided which is arranged to actuate the valve piston 181 at both ends of the table stroke or at either end of the table stroke. In the preferred construction, this is accomplished by means of the cam 182 which is carried by the lever 143. The cam 182 is provided with three surfaces, namely, a surface 194 which in an operative position serves to cause a transverse feeding movement of the carriage 28 at each end of the reciprocatory stroke of the longitudinally movable table 33. A cam surface 195 on the cam 182 serves when in an operative position to cause a transverse feeding movement of the carriage 28 when the longitudinally movable table 33 is at the left-hand end of its stroke, as viewed in Figs. 1 and 3. The cam 182 is provided with a further cam surface 196 which serves when in an operative position to cause a transverse feeding movement of the carriage 28 when the longitudinally movable table is at the right-hand end of its reciprocatory stroke.

A suitable adjusting means is provided to regulate and control the position of cam 182 so as to move cam surfaces 194, 195 or 196 into an operative position relative to the valve roller 183. As illustrated in the drawings, this adjusting mechanism may comprise a manually operable handle 197 which is fixedly mounted on the collar 198 on the upper end of a sleeve 199 which is in turn rotatably mounted in an aperture 200 in the carriage 28. The lower end of the sleeve 199 is provided with a gear segment 201 which meshes with a gear 202 which is fixed to cam 182. The cam 182 and gear segment 202 are rotatably mounted on a stud 203 fixedly mounted on a lever 145 carrying the stud 203, gear 202 and cam 182 and which is keyed to a sleeve 144 which is formed to turn with the reversing lever 143 when the same is actuated by the table reversing dogs 140 and 141. In order that the cam 182 may be located in any one of three positions relative to the reversing lever so as to cause a transverse feeding movement of the carriage 28 either at

both ends of the table stroke or at either end of the table stroke, a spring-pressed ball 206 is provided on the enlarged head 207 of sleeve 144. The ball 206 is adapted to be located in any one of three depressions or recesses in collar 198, in 5 a recess 208, 209 or 210, depending upon the transverse feed desired. By swinging the control lever 197, the collar 198 and sleeve 199 may be rotated to shift the position of the cam 182 and may be located in one of three positions by the spring- 10 pressed ball 206 cooperating with the recesses 208, 209 and 210 to swing cam face 194, 195 or 196 into operative position relative to the valve actuating roller 183, thus permitting a readily accessible means for obtaining the desired transverse 15 feeding movement of the carriage 28.

Table loading position

It is desirable to provide a suitable means for readily positioning the longitudinally movable 20 table 33 in an inoperative or loading position which, as illustrated, may be when the table 33 is in its extreme right-hand position, as viewed in Fig. 1. In order that the table may be moved to such a position, it is desirable to provide a 25 readily accessible means for rendering the dogs or reversing lever 143 ineffective so as to allow the table 33 to travel to a position beyond its normal reciprocatory stroke. As illustrated in the drawings, this may be accomplished by pivotally 30 mounting the lever 143 on a horizontally positioned pin or stud 212 which permits the lever 143 to be rocked in a vertical plane so that when desired a manually operable lever 213 projecting from lever 143 may be raised to position 213a so 35 as to lower the effective end of reverse lever 143 so that it is below the path of travel of the dogs 140 which permit the table 33 to travel beyond its normal reciprocatory stroke toward the right.

As illustrated in the drawings, when lever 213 40 is raised to its inoperative position 213a, to allow the table to travel to a loading position, this idle stroke of the table is continued until the dog 119 engages the projection 120 of lever 115 and shifts the throttle valve 161 to a closed position to stop 45 the table movement at the end of its idle stroke. By adjusting the position of the dog 119, the table may be stopped in any desired position beyond the normal reciprocatory stroke of the table.

Automatic table stop

It is desirable to provide a suitable means for automatically stopping the transverse movement of the carriage 28 after it has traversed transversely through a predetermined extent, so that 55 the grinding wheel has ground the entire surface of the work to be ground, and to automatically run the table to an inoperative or loading position. This is preferably accomplished by an adjustable dog mechanism comprising the adjustably mounted dogs 215 and 216 which are adjustably supported in a T-slot 217 on base 10. The dogs 215 and 216 are adapted to be engaged by a V-shaped projection 218 on a rock arm 219 which is fixedly connected to a rock shaft 220. 60 A lever 221 is mounted on the other end of the rock shaft 220 and is arranged to engage the lower end of a rod 222 which is slidably mounted within the sleeve 144. The upper end of rod 222 engages a pin 223 on the reversing lever 143. 70 The rock arm 219, rock shaft 220, lever 221 and rod 222 are all carried by the carriage 28. As the carriage 28 is moved transversely during grinding, the V-projection 218 will engage either the adjustable dog 215 or 216 after a predetermined 75

transverse movement. When the V-shaped projection 218 rides up on either of the dogs 215 or 216, as illustrated in broken lines in Fig. 6, the rock arm 219 will be rocked in a counterclockwise direction, also rocking the rock shaft 220 and lever 221 in a counterclockwise direction to raise the rod 222. The rod 222 butting against the pin 223 serves to rock the reverse lever 143 in a clockwise direction into position 213a, which 10 serves to depress the operative end of reversing lever 143 so that dog 140 will pass over the lever and the table 33 will automatically move toward the right to an inoperative or loading position. By adjusting the position of dogs 215 and 216, 15 the automatic transverse movement of the work supporting carriage 28 may be varied according to the surface of the work piece which it is desired to grind.

The shaft 220 is resiliently held in an operating 20 position with the lever 219 in the path of the dogs 215 and 216 by means of a spring 214. When it is desired to start the table reciprocation, the shaft 220 is moved toward the right (Figs. 1 and 3), against the tension of spring 214, a sufficient 25 distance to move lever 219 out of the path of the dogs 215 and 216. This movement allows the reverse lever 213 to move from position 213a into an operative position with projection 143 in the 30 path of dogs 140 and 141.

The operation of this machine will be readily apparent from the foregoing disclosure. The operator places the work pieces 36 to be ground on the table 33, adjusts the position of dogs 119, 35 140, 141, 215 and 216. The motor is then started to rotate the grinding wheel and the longitudinal reciprocation of the table 33 is started by the shifting of the lever 218 out of the path of the dogs 215 and 216, then pulling out on the throttle valve and stop control valve knob 110 and shifting the reverse lever 213 into a reverse position. This serves to allow fluid under pressure to exhaust from the inactive side of the piston 43 and thereby cause the table to start its grinding 40 stroke. By proper adjustment of the dogs above mentioned, the table 33 and carriage 28 may be moved longitudinally and transversely to grind the surface of the work to the required extent. By adjustment of the lever 197, the cam 182 45 may be positioned so that a transverse feeding movement of the carriage 28 may be caused at either or both ends of the longitudinally movable table stroke.

Having thus described my invention, what I 50 claim as new and desire to secure by Letters Patent is:

1. A grinding machine comprising a base, a rotatable grinding wheel, a vertically movable slide to support said wheel slide, a transversely movable carriage on said base, a longitudinally reciprocable work table on said carriage, means to feed the wheel slide toward and from the work table, means including a hydraulically actuated pawl and ratchet mechanism to cause a transverse feeding movement of said carriage, means including a piston and cylinder operatively connected between said carriage and table to reciprocate the table longitudinally, means including a lever and reverse valve to automatically change the direction of movement of said table, and a fluid pressure mechanism independent of said fluid pressure table reciprocating mechanism including a control valve actuated in timed relation with the reverse lever to actuate said pawl and 60 ratchet mechanism at either or both ends of the 65

table stroke to cause a transverse feeding movement of the carriage.

2. A surface grinding machine comprising a base, a rotatable grinding wheel, a vertically movable slide supporting said wheel, a feeding mechanism to adjust the slide vertically relative to the base, a longitudinally movable work supporting table, a transversely movable carriage which supports said longitudinally movable table, a piston and cylinder mechanism interposed between the transverse slide and the table to cause a reciprocation of the work table, means including a reversing valve actuated by movement of the table to cause a reversal in direction of the table movement after it has traversed to a predetermined position, a feeding mechanism operatively connected to cause a transverse movement of said slide and table, means actuated by and in timed relation with the table reciprocation to cause said feeding movement at the end 20 of the table stroke, and automatically actuated means to terminate said transverse feed and the longitudinal feed when the wheel and the work have been moved relatively in a transverse direction, stopping the work table in its right-hand 25 end or loading position.

3. A grinding machine comprising a base, a rotatable grinding wheel, a vertically movable slide for said wheel, a transversely movable carriage mounted on said base, a longitudinally movable work supporting table on said carriage, means to feed said wheel slide vertically to adjust the position of the wheel relatively toward and from the work, means including a reversing mechanism to reciprocate said table, a reversing lever and adjustable dogs interposed between the carriage and table to actuate said reversing mechanism, means including a feeding mechanism to cause a transverse movement of the carriage and table relative to the grinding wheel to feed the work transversely, and means including adjustable dogs on said base which serve to render said longitudinally movable table reversing mechanism inoperative after the carriage has moved transversely to a predetermined extent to stop the longitudinal movement of the table after a predetermined grinding operation.

4. A grinding machine comprising a base, a rotatable grinding wheel, a vertically movable slide on said base to support said wheel, a transversely movable carriage on said base, a longitudinally movable work table on said carriage, a reversing mechanism interposed between the carriage and table to reciprocate said table longitudinally, means including a reversing lever and adjustable dogs to actuate said reversing mechanism, means to cause a transverse feeding movement of said carriage to move the work piece transversely relative to the grinding wheel, means including adjustable dogs on said base and a lever mechanism to render said table reversing lever inoperative after the carriage has been moved transversely to a predetermined extent to allow the table to move to and stop at a loading position beyond the normal reciprocatory stroke.

5. A grinding machine comprising a base, a rotatable grinding wheel, a vertically movable wheel slide to support said wheel, a transversely movable carriage on said base, a longitudinally movable work table on said carriage, means to move the wheel slide vertically to cause said wheel to move relatively toward or from the work table, means including a hydraulically actuated pawl and ratchet mechanism to cause a transverse 70

- feeding movement of said carriage to move the work table transversely relative to the grinding wheel, means including a piston and cylinder interposed between the carriage and work table to reciprocate said table, means including a reverse lever and valve to reverse the direction of movement of said table, adjustable dogs on said table to actuate said reversing mechanism, and means including adjustable dogs on said base which serve 5 to render said table reversing dogs ineffective after the carriage has moved transversely to a predetermined extent to allow the table to traverse by the normal reciprocatory stroke and to stop in a predetermined loading position.
- 15 6. A grinding machine comprising a base, a vertically movable slide, a rotatable grinding wheel, a transversely movable carriage mounted on said base, a longitudinally movable work table, means including a pawl and ratchet mechanism 20 to cause a transverse feeding movement of said carriage to move the work piece transversely relative to the grinding wheel at the ends of the table stroke, means including a fluid pressure piston and cylinder operatively connected between the carriage and table to reciprocate said table, a reversing mechanism including a lever and a valve to change the direction of movement of said table, adjustable dogs on said table arranged to actuate said lever to reverse the table 25 at either or both ends of its stroke at a predetermined position, means including adjustable dogs on said base and a pivotally mounted lever engaged thereby which are arranged to render said reversing lever inoperative after the carriage 30 has moved transversely to a predetermined extent to allow the table to travel beyond the reversing dogs, and means including a third adjustable dog on said table to stop said longitudinally movable table in a predetermined loading position.
- 35 7. A grinding machine comprising a base, a rotatable grinding wheel, a movable wheel slide to support said wheel, a longitudinally movable table, means to move the wheel slide to cause the wheel to move relatively toward and from the work 40 table, means including a piston and cylinder to reciprocate said table, means including a reversing lever and valve to reverse the direction of movement of the table, adjustable dogs on said table to actuate said reversing lever, a control valve arranged to throttle the flow of fluid to said system, means to rotate said valve to regulate the speed of movement of said table, means 45 to render said reversing lever ineffective to allow the table to move beyond its normal reciprocatory stroke, and means including a third dog on said table to move said control valve endwise to stop the table when it has moved to a predetermined loading position beyond the normal reciprocatory stroke.
- 50 8. A hydraulic grinding machine table reciprocating mechanism comprising a longitudinally movable table, a fluid pressure system including a piston and cylinder operatively connected to reciprocate said table, a reversing valve arranged to reverse the direction of movement of said table, means including a reversing lever and a pair of adjustable dogs on said table to actuate said reversing mechanism, a control valve which 5 serves to regulate the speed of movement of said table, means to render said reversing lever inoperative to allow the table to pass beyond the normal reciprocatory stroke, a third dog on said table, a lever in the path of said third dog and arranged to move said control valve to a closed position to stop the table movement in a predetermined loading position, and a resilient connection between the lever and control valve which permits the operator to open the control valve so 10 as to start the table reciprocation after a new piece of work has been loaded on the machine.
- 15 9. A grinding machine comprising a base, a rotatable grinding wheel, a wheel slide to support said wheel, a longitudinally movable work 20 table, means to move the wheel slide to cause the wheel to move relatively toward and from the work table, means including a hydraulically actuated pawl and ratchet mechanism to cause a relative transverse feeding movement between 25 the wheel and work, means including a piston and cylinder to reciprocate said table, means including a reversing lever and valve to reverse the direction of movement of said table, a control valve arranged to admit fluid to said hydraulically actuated pawl and ratchet mechanism to cause a transverse feeding movement, and an adjustable cam associated with said reverse lever for actuating said control valve which serves to actuate the control valve when the reversing 30 lever is shifted at reversal to cause a transverse feeding movement at either or both ends of the work table stroke.
- 35 10. A grinding machine comprising a base, a rotatable grinding wheel, a wheel slide to support said wheel, a longitudinally movable work table, means to move the wheel slide to cause the wheel to move relatively toward and from the work table, means including a hydraulically actuated pawl and ratchet mechanism to cause a relative transverse feeding movement between 40 the wheel and work, means including a piston and cylinder to reciprocate said table, means including a reversing lever and valve to reverse the direction of movement of said table, a control valve arranged to admit fluid to said hydraulically actuated pawl and ratchet mechanism to cause a transverse feeding movement, an adjustable cam associated with said reverse lever for actuating said control valve, which serves to actuate the control valve when the reversing lever is shifted at reversal to cause a transverse feeding movement at either or both ends of the work table 45 stroke, and means to adjust the extent of traverse movement between said wheel and work at reversal.
